UNITED STATES PATENT OFFICE.

JOHN CLAYTON BACKUS, OF SMETHPORT, PENNSYLVANIA.

WINDOW-FRAME FOR FABRICS

1,324,872.

Specification of Letters Patent. Patented Dec. 16, 1919.

Application filed July 31, 1918. Serial No. 247,606.

To all whom it may concern:

Be it known that I, JOHN CLAYTON BACKUS, citizen of the United States, residing at Smethport, in the county of Mc- 5 Kean and State of Pennsylvania, have invented certain new and useful Improvements in Window-Frames for Fabrics, of which the following is a specification.

This invention relates to an improved 10 window frame particularly designed for use in mounting windows upon automobile tops or curtains but which is, however, adapted for general use in securing a pane of window glass upon fabric.

15 The invention has as its primary object to provide a frame which may be stamped complete from suitable sheet metal and will thus be capable of production at minimum cost and wherein the frame, holding a window pane, may be quickly and easily secured upon a piece of fabric without the aid of separate fastening devices, to the end that the frame may be applied with a minimum expenditure of time and labor.

20 25 A further object of the invention is to provide a frame wherein a water tight joint will be formed not only between the fabric and the window pane but also between the fabric and the coacting plates of the frame 30 for thus effectually excluding the weather at the window opening.

The invention has as a further object in this connection to provide a construction wherein the coacting plates of the frame will 35 be clamped together by suitable clamping means carried by one of the said plates and wherein the stress of the said clamping means will be wholly distributed between the inner and outer edges of the plates to 40 thus obtain a maximum clamping effect tending to form water tight joints between the window pane and the fabric as well as between the fabric and the plates.

45 And the invention has as a further object to provide a construction wherein the clamping means employed between the plates will act to center the window frame with respect to the window opening in the fabric.

50 Other and incidental objects will appear as the description proceeds. In the drawings, wherein I have illustrated the preferred embodiment of the invention, and wherein similar reference characters designate corresponding parts throughout the 55 several views:

Figure 1 is a front elevation showing my

improved frame mounted on a conventional curtain and supporting a window pane, and

Fig. 2 is a fragmentary sectional view taken on the line 2—2 of Fig. 1, this view being on a greatly enlarged scale in order to more clearly illustrate the details of construction of the frame.

Referring now more particularly to the drawings, I have, in order to clearly bring out the construction and mounting of the window frame, shown the frame in operative position upon a conventional curtain 10, supporting a window pane 11 over a window opening 12 in the curtain. The window pane may be of glass or other suitable transparent material. In carrying the invention into effect, I employ coacting clamping members or plates A and B respectively, the plate A forming the inner plate of the frame and the plate B the outer plate of the frame. These plates may be of annular configuration or other desired shape, according to the character of window preferred, and are preferably stamped from suitable resilient sheet metal. In the drawings, the curtain is illustrated as being provided with a circular window opening and the frame is accordingly also shown as being circular to surround this opening, the inner diameter of each of the plates being substantially equal to that of the said opening.

Substantially midway between its side edges, the plate A is bent to provide a continuous rib 13. From this rib the inner margin of the plate is bent to form an outwardly bowed pane engaging flange 14 having a gripping face 15 at its outer edge. From the rib 13 the outer margin of the plate is bent outwardly to define a channel 16 and from this channel is continued to provide an inwardly directed fabric gripping flange 17 disposed at an acute angle to the plane of the gripping face 15 of the flange 14 of the said plate. Struck from the outer margin of the plate at suitable spaced points thereon, is a series of gripping tongues 18 extending from the crown of the rib 13.

The plate B is of slightly less width than the plate A and is adapted to mate therewith. This plate B is formed midway between its side edges with a continuous shoulder 19 from which the inner margin of the plate is bent to provide an outwardly bowed pane engaging flange 20 formed at its outer edge with a gripping

2
face 21 adapted to register with the gripping face 15 of the flange 14 of the plate A. From the shoulder 19, the inner margin of the plate B is bent to provide an outwardly bowed fabric gripping flange 22 adapted to fit within the channel 16 of the plate A to coact with the flange 17 of this latter plate. Formed in the plate B at suitable points thereon for receiving the tongues 18 of the plate A is a series of spaced openings 23 disposed adjacent the base of the shoulder 19 of the said plate. It is now to be observed that the plates A and B, as thus described are of such construction that each 15 of the said plates may be struck at a single operation from a piece of suitable sheet metal so that the frame may accordingly be produced at minimum cost.

In applying the frame, the plate A is first 20 placed against the inner side of the curtain with the central opening through the plate registering with the window opening 12 in the curtain, the tongues 18 being initially straight so that these tongues may thus be 25 forced through the fabric of the curtain for centering the plate with respect to the window opening in the curtain. The pane 11 is then positioned against the flange 14 of the plate beneath the margin of the curtain 30 rounding the window opening therein so that, as particularly shown in Fig. 2 of the drawings, the curtain will overlie the pane upon its outer side. The plate B is then positioned over the plate A in mating relation thereto, receiving the clamping tongues 35 18 through its openings 23. The flange 20 of the plate B will thus overlie the margin of the curtain surrounding the window opening 12, therein while the flange 22 of the said 40 plate will be received within the channel 16 of the plate A bearing over the curtain. Thus, the flange 17 of the plate A will coact with the flange 22 of the plate B for centering this latter plate upon the plate A so that 45 the center opening through the plate B will register with the center opening in the plate A while the gripping face 21 of the flange 20 of the plate B will be disposed to contact with the margin of the curtain surrounding 50 the window opening 12 immediately at the periphery of the said opening. Having initially positioned the plate B upon the plate A, the free extremities of the tongues 18 are then bent outwardly and downwardly 55 against the flange 22 of the latter plate, as illustrated in the drawings, for tightly clamping the plates together.

Attention is now directed to the fact that when the plates A and B are clamped together, the curtain will be wedged between the gripping flanges 17 and 22 of the plates at the outer edges of the plates so that a watertight joint will be formed between the fabric of the curtain and the plates. Furthermore, it will be seen that since the flange

17 rises above the plane of the gripping face 15 of the flange 14 of the plate A, this flange is adapted to support the outer edge of the flange 22 of the plate B to fulcrum thereon in a plane substantially midway between the gripping faces 15 and 21 of the plates. Consequently, since the flanges 14 and 20 of the plates are outwardly bowed to extend in spaced relation to the periphery of the pane 11 at each side thereof, the plates will, when the tongues 18 are tightened to clamp the plates together, tend to rock upon each other at their outer edges and accordingly swing the gripping faces 15 and 21 of the flanges 14 and 20 into binding contact one with the inner side of the pane and the other with the curtain at the outer side of the pane. The pane will accordingly be yieldably gripped between the flanges 14 and 20 of the plates to provide a watertight joint between the pane and the fabric of the curtain. The weather at the window opening in the curtain will thus be effectually excluded. Furthermore, in this connection, it is to be noted that since the plates A and B of the frame 90 are formed to clamp the pane at their inner edges, only by the gripping faces 15 and 21, and are also formed to clamp the fabric only at their extreme outer edges, all of the clamping stress exerted by the tongues 18 95 will be distributed between these two points of clamping action. Extreme pressure will thus be exerted by the plates upon the fabric of the curtain to accordingly provide sealed joints between the curtain and the frame as 100 well as between the curtain, the frame, and the window pane.

I, therefore, provide a highly efficient construction for the purpose set forth and a window frame which, as will be seen in view 105 of the preceding description, may be readily applied with a minimum expenditure of labor and time. Furthermore, the necessity for the use of separate fastening devices for mounting the frame upon the fabric is eliminated.

Having thus described the invention, what is claimed as new is:

1. A window frame including coacting frame plates deflected at their outer margins 115 to provide a pair of fabric gripping flanges and deflected at their inner margins to provide a pair of window pane gripping flanges, the intermediate portions of the plates being directed inwardly to define shoulders projecting toward each other between the pairs of flanges and adapted to coact with the edge of a window pane gripped by the latter pair of flanges for centering the pane with respect to the plates, one of the plates being 125 provided with means connecting the intermediate portions of the plates with each other.

2. A window frame including coacting frame plates deflected at their outer margins 130

to provide a pair of fabric gripping flanges and deflected at their inner margins to provide a pair of window pane gripping flanges, the intermediate portion of one of the plates being directed inwardly toward the other between the pairs of flanges, and means connecting the intermediate portions of the plates with each other.

3. A window frame including coacting frame plates one deflected at its outer margins to provide flanges, one of said flanges being adapted to coact with the other frame

plate for gripping a fabric and the other flange being adapted to coact with the latter frame plate for gripping a window pane, 15 the intermediate portion of the first plate between said flanges being directed inwardly toward the other plate to provide a shoulder for centering a pane with respect to the plates; and means for connecting the plates 20 with each other.

In testimony whereof I affix my signature.

JOHN CLAYTON BACKUS. [L.S.]
